UNITED STATES PATENT OFFICE.

ALFRED F. C. LOTZ, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

SWITCH-OPERATING MECHANISM.

Application filed June 1, 1925. Serial No. 33,886.

This invention relates to mechanism for operating switches, more particularly to mechanism for closing an oil switch and for tripping the same open, although of course 5 it may be used wherever found desirable.

According to my invention I employ a rotary shaft which, in the preferred form of the invention, is the operating shaft of the switch, and I provide in conjunction therewith means for automatically or manually tripping the switch open and for manually restoring the switch to closed position. The same motion which restores the switch to closed position restores the automatic trip to 15 normal position, and the same means which manually trips the switch may reset it and restore the automatic and manual tripping means to their normal positions.

The mechanism employed according to my 20 invention is of simple, rugged, and inexpensive construction. The operating mechanism is characterized by a minimum of inertia, so that the oil switch may open with great rapidity. The strain upon the parts is low 25 and long life and satisfactory operation are thereby assured, and furthermore the mechanism which I provide positively holds the switch closed and makes both the automatic and manual tripping operations positive in 30 action and with few parts.

In my co-pending application, Case 8, Serial No. 753,028, filed December 1, 1924, I have shown a suitable oil switch employing 35 a rocking or rotary shaft which is adapted to be operated by the present mechanism, but it will be understood that the invention is not limited to the combination of that particular switch with the present mechanism, but that the present mechanism is new in 40 combination with any type of switch which employs the rocking or rotary shaft.

Means preferably a spring, may tend to move or rock the switch operating shaft in one direction, and a relatively small angular 45 motion of this shaft is sufficient, as more fully explained in my above referred to co-pending application.

In order to acquaint those skilled in the art with the manner of constructing and operating my invention, I shall now describe 50 an embodiment of the same in conjunction with the accompanying drawings.

In the drawings:

Figure 1 is a front elevational view of a 55 device embodying my invention with the

cover removed, the positions of the parts before tripping being shown in solid lines and after tripping manually, in dotted lines;

Fig. 2 is a view similar to Fig. 1, showing in dotted lines the positions of the various 60 operating parts after automatic tripping;

Fig. 3 is an end elevational view with the cover in vertical section;

Fig. 4 is a front elevational view with the cover in place and showing the operating 65 lever and its mounting;

Fig. 5 is a horizontal end sectional view taken on line 5—5 of Fig. 2;

Fig. 6 is an enlarged sectional view taken 70 on line 6—6 of Fig. 1 and brings out in greater detail the manner of assembling the clutch mechanism for the operating lever;

Fig. 7 is a plan view of the trip mechanism looking at it from above with the cover in 75 horizontal section;

Fig. 8 is a perspective view of the operating clutch; and

Fig. 9 is a similar view of the setting lever.

The square shaft 10 prolonged forms the 80 shaft of the switch mechanism, such as disclosed in my co-pending application above referred to. Rocking of this shaft in one direction serves to open the switch by separating the contacts of said switch to the desired extent and rocking or movement of the shaft in the reverse direction closes the 85 switch.

The switch shaft, in the present case, is rocked through approximately 30°, and by 90 this small rocking movement the switch may be completely opened or closed. The shaft 10 extends through a bushing 11, which is journaled in a babbitt bearing 12 in the bearing member 13. The bearing member 13 95 is preferably cast integral with the base plate 14.

The spring which operates the shaft 10 may be arranged in any suitable or preferred 100 manner. In Fig. 3, for purposes of illustration, I have shown an arm 100 secured on shaft 10, a tension spring 101 being secured at one end to this arm and at its other end to a relatively fixed element, at 102, this spring urging the shaft in switch opening direction.

A shaft lever 15 is mounted on the shaft 10 substantially adjacent the bushing 11. It is provided with a slot which lies along its longitudinal axis through the opening pro- 110

vided for the shaft. A bolt 16 is adapted to pass through the transverse opening in the two separate clamping portions formed by the slot, and serves to clamp the lever 15 securely to the shaft by threading into the nut 17, so as to draw the separate clamping portions tightly against the shaft. A lug 14', which is preferably cast integral with the base plate 14, serves to limit the counter clockwise movement of the shaft lever 15.

The lower end of the shaft lever 15 is pivotally secured at 15' to a toggle link 18. The toggle link 18 at its opposite end is pivotally secured at 18' to a setting toggle link 19. The setting toggle link 19 has an angularly offset portion 20 integral therewith, which terminates in a horizontal nose or lip 21. The lip 21 co-operates with a relatively rectangular notch in an angular toggle latch 22. The toggle latch 22 is pivotally secured at 22' to the toggle link 18. The portion of the toggle, as just described, merges into a rectangular portion, which is disposed generally horizontally when the trip mechanism is set.

The opposite end of the setting toggle 19 is pivotally connected at 19' to the lower end of the setting lever 23. The upper portion of the setting lever 23 is provided with a clutch member 24, as shown in Fig. 9. This clutch member is integral with the lever 23 and has an integral protruding member 25, which is disposed centrally between the jaws 26 and adjacent one of the faces of the lever. The radius of the protruding member 25 is greater than that through the circumference of the jaws 26, and its thickness or width is less than that of the jaws 26, as shown. The cam portion 27 of the clutch member 28 operates in this space between the jaws 26 and the inner face of the protruding member 25. The cam portion 27 has an angular movement of approximately 30 degrees in the space between the jaws 26. Both the lever 23 and the clutch 28 are mounted on the shaft 29. The lever 23, however, is adapted for rotative movement on the shaft, while the clutch 28, the cam portion of which lies in a space between the jaws 26, is secured to the shaft by means of a suitable pin 30.

The shaft 29 is journaled in a support or bracket member 31 which is preferably made integral with the base plate 14. In Fig. 6, the shaft 29 is shown as being journaled in a babbitt bearing 32 at one end and in the support member 31 at the opposite end. However, I do not wish to limit myself to this particular way of mounting the shaft, for it is obvious that any other method may be used, such as the provision of separate bushings or bolts for either end of the shaft. A latch 33 is pivotally mounted on a wall 34 by means of the screw 35. The latch 33 is provided with an offset portion 33', which is adapted to ride on the surface of the cam

27, of the clutch member 28. One end of the latch 33, which is adjacent the offset portion, co-operates with one face of the protruding member 25 of the clutch 24 when the latch is in its lower position, but is adapted to disengage from said protruding member when the latch is raised by movement of the cam 27 to its upper position, so as to permit movement of the lever 23.

At the lower end of the base plate 14 is mounted a solenoid bracket 36 as by means of screws 37. This bracket is provided with three separate support members 38 to which the magnets 39 are secured as by the screws 40. It is to be understood that the number of support members may vary, depending on the kind of circuits in which the mechanism is to be used. Each of the magnets 39 is generally U-shaped and is provided at its upper side with an opening into which is threaded a pole piece 41. Adapted for reciprocating motion in the pole pieces 41 are the pins 42 which thread into the plungers 43. Plungers 43 extend through an opening in the magnets 39 into openings in the support members 36. Their downward travel, however, is limited by means of the screws 44 which may be locked in any desired position by means of the nuts 45.

The solenoids may be wound on bobbins of bakelite or otherwise suitably insulated. These bobbins are secured to the magnets 39 by means of the screws 40, which also serve, as heretofore explained, to fasten the magnets to the solenoid bracket 36.

Mounted on the upper side of the magnets 39, as by the screws 46, is a bearing member 47 on which is pivotally mounted the release lever 48 by means of the bearing pins 49. The release lever 48 includes a longitudinal angle portion. It is mounted by means of a pair of arms which extend integrally from the angle portion to the pins 49 and are pivoted or swingably mounted thereon. Approximately one-third of the distance from one end of the lever is a relatively rectangular web, which extends outwardly from the inner faces of the angle portion. This web is indicated by the numeral 52 and upon its upper edge rests the toggle latch link 22.

The lower portion of the switch is provided with a cover 53 which may be secured to the base plate by means of the bolts 54. A suitable pipe or conduit means 55 may be fitted into the lower side of this cover to permit the entrance therethrough of the conductors 56 to the solenoids. This lower cover 53 is provided with a flange 55', on which the upper cover 56 is adapted to seat. The upper cover 56 may be secured to the flange 55' by means of screws 57. Cover 56 is provided with a pair of integral lugs 58 and 59. A similar lug 60, which is integral with the handle 61, is adapted to co-operate with the inner faces of the lugs 58 and 59,

so as to limit the angular movement of the handle 61. The handle is secured to the shaft 29 by means of a pin 62. It is provided with an arm 63 which is provided at its free end with a balancing member 64. The arm itself is bent at substantially right angles so as to facilitate tripping and resetting of the switch.

The device operates as follows:

When the solenoids are energized, the magnetic flux created thereby and acting on the plungers 43, will cause them to move upward, so that the pin 42 will force the release lever 48 to swing around the bearing member 47. The toggle latch 22, which rests freely on the upper surface of the web 52, will also be forced upward. Since the toggle latch is pivotally connected to the toggle link 18, it will also form a toggle link to swing around its pivotal connection with the lever 15, thereby permitting the lip 21 to be released from the toggle latch 22. When this occurs, the spring which actuates the switch shaft throws the operating lever for this shaft into the dotted line position shown in Fig. 2. Likewise, the toggle link and the setting link are thrown out of this straight line or 180° position into that shown by the dotted lines in the same figure. When the mechanism is tripped automatically, the lever 23 is not set in motion, it being held against rotation by the latch 33, which engages with the protruding member 25 thereon. The trip mechanism is reset manually by moving the hand lever 61 in a counter clockwise direction, so as to bring the lug 60 against the face of the lug 58. In doing so, the latch 33 is raised by the cam 27, thereby permitting the lever 23 to move into the dotted line position, shown in Fig. 2. This permits the toggle link and the setting toggle to set back into a straight line relation. Now, if the hand operating lever 61 is turned in a clockwise direction, it will shift the levers 15 and 23 and the toggle link and setting toggle back into their original positions, as indicated by the solid lines in Figs. 1 and 2.

In tripping the mechanism manually, the toggle link and the setting toggle do not get out of their straight line or 180° relationship. A counter clockwise movement of the hand operating lever 61 will cause the cam 27 to lift the latch 33 out of engagement with the protruding member 25, so that the lever 23 may be pushed back, together with the lever 15 and the link mechanism connected between the levers 15 and 23 by the spring which actuates the operating shaft of the switch. It will be observed that in tripping the mechanism by hand, that the toggle link and the setting toggle do not get out of their straight line relationship, nor does the trip 21 of the setting toggle 20 become disengaged with the opening pro-

vided for it in the toggle latch 22. The toggle latch 22 is engaged simply with the surface of the integral member 52 of the release lever 48.

I do not intend to be limited to the details shown or described.

I claim:

1. In combination, a switch operating shaft, means for turning said shaft in one direction, an operating lever mounted on said shaft, a manual operating lever and a shaft therefor eccentric to the switch operating shaft, link mechanism pivotally connected with the lever on said operating shaft and with said manual operating lever, a protruding member integral with said manual operating lever, means adapted to engage with said protruding member to hold said switch operating shaft against rotation by said turning means, and means for disengaging said last named means from said protruding member so as to permit movement of said switch operating shaft.

2. In combination, a switch operating shaft, an operating lever mounted on said shaft, means tending to turn said shaft in one direction, a manual operating shaft, a manual operating lever mounted on said manual operating shaft, link mechanism pivotally connecting said shaft operating lever with said manual operating lever, a cam member mounted on said manual operating shaft, a protruding member integral with said manual operating lever, means adapted to engage with said protruding member to prevent rotation of said shaft by said turning means, the means adapted to engage with said protruding member being also adapted to co-operate with the cam member on said manual operating shaft which is adapted to move said means out of engagement with said protruding member so as to permit rotation of said switch operating shaft by said turning means by movement of said cam member.

3. In a device of the class described, in combination, a plate member, a support integral with said plate member, a manual operating shaft mounted in said support, a manual operating lever having an integral protruding member mounted on said shaft, a clutch member having a cam member integral therewith mounted on said shaft and adapted for engagement with said manual operating lever, and means adapted to engage with said protruding member and to be brought out of engagement with said protruding member by said cam member when said shaft is turned.

4. In a device of the class described, a plate member, a support member integral with said plate member, a manual operating shaft mounted in said support member, a manual operating lever having an integral protruding portion mounted on said shaft,

- a clutch member mounted on said shaft and adapted to engage with said manual operating lever, an integral cam member for said clutch, means adapted to engage with said protruding member for holding same against rotation when a force is exerted against said manual operating lever and to be disengaged with said protruding member by said cam member when said manual operating shaft 70 is rotated, said means comprising a latch pivotally mounted to means on said plate member and having an end portion which is adapted to engage with one face of said protruding member, and an offset portion 75 which is adapted to ride on said cam member.
5. In combination, a rocking shaft, means tending to rock said shaft, an operating lever on said rocking shaft, a manually operated shaft, an operating lever mounted thereon, a cam member on said manually operated shaft, means adapted to cooperate with said cam member for holding said shaft against movement, and link mechanism for interconnecting the levers on both of said shafts, said link mechanism serving to move both shafts through substantially the same proportional angular distance when said holding means is released.
- 20 6. In combination, a rocking shaft, means tending to rock said shaft, an operating lever on said rocking shaft, a manually operated shaft, an operating lever mounted thereon, a cam member on said manually operated shaft, means adapted to cooperate with said cam member for holding said shaft against movement, link mechanism interconnecting the levers on both of said shafts, and means for releasing said holding means to permit movement of both of said shafts through substantially the same proportional angular distance by said link mechanism.
- 25 7. In combination, a rocking shaft, means tending to rock said shaft, an operating lever on said rocking shaft, a manually operated shaft, an operating lever thereon, a pair of pivotally connected links interconnecting said lever, said links having a straight line relationship when holding said rocking shaft, and automatic means for breaking the straight line relationship of said links to 100 permit turning of said rocking shaft by said rocking means.
- 30 8. In combination, a rocking shaft, means tending to rock said shaft in one direction, means including a pair of pivotally connected links for holding said rocking shaft against action by said first means when said links are in a straight line relationship, manually operated means for tripping out said holding means, and automatic means for breaking the straight line relationship of said links.
- 35 9. In combination, a rockably mounted switch operating shaft urged in switch open- 105
- ing direction, a lever secured on said shaft, a rockably mounted arm, a toggle connecting the arm and the lever, means normally holding said toggle fully extended in straight line position and on dead centre, means holding the arm against turning movement in switch opening direction, and means for releasing and breaking the toggle permitting movement of the lever in switch opening direction independently of the arm.
10. In combination, a rockably mounted switch operated shaft urged in switch opening direction, a lever secured on said shaft, a rockably mounted arm, a toggle connecting the arm and the lever, means normally holding said toggle in straight line position and on dead centre, means holding the arm against turning movement in switch opening direction, means for manually releasing and resetting the arm, and means for releasing 110 and breaking the toggle.
11. In combination, a rockably mounted switch operating shaft urged in switch opening direction, a lever secured on said shaft, a rockably mounted arm having movement about an axis eccentric to the shaft, a toggle connecting the arm and the lever, means normally holding said toggle in straight line position and on dead centre, means holding the arm against turning movement in switch opening direction, and means for releasing 115 and breaking the toggle.
12. In combination, a rockably mounted switch operating shaft urged in switch opening direction, a lever secured on said shaft, a rockably mounted arm having a movement about an axis eccentric to the shaft, a toggle connecting the arm and the lever, a latch pivoted on one member of the toggle and having operative engagement with the other toggle member, said latch holding the toggle in straight line position and on dead centre, means holding the arm against turning movement in switch opening direction, the latch having a lower angularly disposed arm, a trip lever, the latch arm normally resting upon the trip lever, and automatic means for projecting the trip lever toward the toggle, tripping the latch to release the toggle and breaking the toggle.
13. In combination, a rockably mounted switch operating shaft urged in switch opening direction, a lever secured on said shaft, a rockably mounted arm having movement about an axis eccentric to the shaft, a toggle connecting the arm and the lever, a latch pivoted on one member of the toggle and having operative engagement with the other toggle member, said latch holding the toggle in straight line position and on dead centre, means holding the arm against turning movement in switch opening direction, the latch having a lower angularly disposed arm, a trip lever, the latch arm normally resting upon the trip lever, automatic means for 120
14. In combination, a rockably mounted switch operating shaft urged in switch opening direction, a lever secured on said shaft, a rockably mounted arm having movement about an axis eccentric to the shaft, a toggle connecting the arm and the lever, a latch pivoted on one member of the toggle and having operative engagement with the other toggle member, said latch holding the toggle in straight line position and on dead centre, means holding the arm against turning movement in switch opening direction, the latch having a lower angularly disposed arm, a trip lever, the latch arm normally resting upon the trip lever, automatic means for 125
15. In combination, a rockably mounted switch operating shaft urged in switch opening direction, a lever secured on said shaft, a rockably mounted arm having movement about an axis eccentric to the shaft, a toggle connecting the arm and the lever, a latch pivoted on one member of the toggle and having operative engagement with the other toggle member, said latch holding the toggle in straight line position and on dead centre, means holding the arm against turning movement in switch opening direction, the latch having a lower angularly disposed arm, a trip lever, the latch arm normally resting upon the trip lever, automatic means for 130

projecting the trip lever toward the toggle tripping the latch to release the toggle and breaking the toggle, and means for releasing and resetting the arm, the toggle being 5 extended by release of the arm and the latch moving into operative position upon extension of the toggle.

14. In combination, a rockably mounted switch operating shaft urged in switch 10 opening direction, a lever secured on said shaft, a rockably mounted arm disposed eccentric to the shaft, a toggle connecting the

arm and the lever, means normally holding said toggle fully extended in straight line position and on dead centre, means holding 15 the arm against turning movement in switch opening direction, and means for releasing and breaking the toggle permitting movement of the lever in switch opening direction independently of the arm.

In witness whereof, I hereunto subscribe my name this 25 day of May, 1925.

ALFRED F. C. LOTZ.
